UNITED STATES PATENT OFFICE.

WILLIAM H. WENDT, OF LITTLE FALLS, MINNESOTA.

PROPELLER ATTACHMENT.

Application filed May 7, 1927. Serial No. 189,589.

This invention relates to improvements in propeller attachments and more particularly to such a device functioning to lessen the effective propelling angle of the propeller blades for the purpose of reducing the speed of a boat or vessel.

The attachment is particularly adaptable for use in connection with small propellers, such as are commonly used on out board propeller mountings, and, in which devices, for 10 motors are usually directly connected with the propeller, that is, no mechanism is provided for varying the speed of the propeller, as is customary on larger boats or vessels, and 15 the purpose of this attachment is to lessen the effective propelling angle of the propeller blades to the extent that the speed of propulsion of the vessel will be considerably reduced, when the attachment is attached to the 20 propeller and the latter is rotating at a given speed.

Other objects of the invention reside in the simplicity and general construction of the attachment, which permits it to be readily attached to and detached from a propeller; the 25 simple means for securely locking it to the propeller; and, in the design of the device, as a whole, which is such that it may readily be applied to propellers of standard construction with a minimum amount of labor.

The particular object of the invention therefore, is to provide an improved attachment for propellers.

Other objects of the invention will appear 35 from the following description and accompanying drawings and will be pointed out in the annexed claims.

In the accompanying drawings there has been disclosed a structure designed to carry 40 out the various objects of the invention, but it is to be understood that the invention is not confined to the exact features shown, as various changes may be made within the scope 45 of the claims which follow.

45 In the accompanying drawings forming part of this specification;

Figure 1 is a side elevation of a propeller, showing the attachment applied thereto;

Figure 2 is a vertical sectional view on the 50 line 2—2 of Figure 1;

Figure 3 is an end view of Figure 1;

Figure 4 is a detailed sectional view on the 55 line 4—4 of Figure 2;

Figure 5 is a side elevation of the propeller 60 with the attachment removed therefrom; and

Figure 6 is a view, showing the attachment removed from the propeller.

In the selected embodiment of the invention here shown, for purposes of disclosure, there is illustrated a propeller, of ordinary 60 construction, comprising blades 2 mounted upon a hub 3, suitably secured to the shaft 4, which is operatively connected to a suitable source of power, not shown.

The novel attachment featured in this invention is shown in Figure 6, and comprises blade portions 5, preferably integrally formed of metal and having a central aperture 6 in the connecting portion 7, between the blades, which is adapted to receive the end of 70 the hub 3, as shown in Figure 3. The inner faces 8 of the blade portions 5 are shaped to coincide with the adjacent or outer faces of the propeller blades when seated thereagainst, as shown in Figure 4. In this figure, it will 75 be noted, that the blade portions 8 are substantially V-shaped in cross section so that when the attachment is secured to the propeller, the effective or outer angle of the propeller blades will be considerably lessened, so thereby causing a reduction in the speed of propulsion of the vessel. The broken line a—a indicates the normal propelling angle of the blades, and the broken line b—b indicates the effective propelling angle of the blades, 85 when the attachment is attached thereto.

Dowel pins 9 are secured to the inner faces of the blade portions 8 of the attachment and are adapted to be received in apertures 10, provided in the propeller blades 2, as shown 90 in Figure 5. The dowel pins 9 are of sufficient length to project through the propeller blades 2 as shown in Figure 4. Each pin is further provided with notches or recesses 11 adapted to be engaged by locking clips 12, 95 yieldably connected with the attachment by means of tension springs 13, shown in Figures 1, 2, and 6. Each clip 12 has a key slot 14 therein adapted to receive a dowel pin.

In attaching this simple device to a propeller for the purpose of reducing the effective propelling force or power of the propeller, the attachment is mounted upon the propeller as shown in Figures 1, 3, and 4, in which position the dowel pins 9 will project 105 through the propeller blades 2. The clips 12 and springs 13 are then brought around to the opposite sides of the propeller blades and the clips engaged with the protruding ends 110 of the dowel pins so that the reduced ends 115

of the key slots 14 will engage the recesses 11 in the pins, thus securely locking the attachment to the propeller in the manner shown in Figures 1, 2, and 4. When thus mounted, it 5 will be noted that the attachment in effect becomes an integral part of the propeller, and as a result of the V-shaped cross section of the blade portions 8, the effective propelling angle of the propeller will be reduced 10 to the extent that when the propeller is rotated in the water at a given speed, the speed of the boat or vessel will be considerably reduced. When it is desired to increase the 15 speed of the vessel, the attachment may be quickly removed from the propeller by simply disengaging the clips 12 from the dowel pins 9, after which the attachment may be detached from the propeller and the speed of the boat will accordingly be increased.

20 I claim as my invention:

1. An attachment for a propeller comprising curved faces formed to be abuttingly engaged with the faces of the propeller blades and shaped to lessen the effective angle of 25 the propeller blades, and spring-actuated clips secured to the attachment and adapted to be lockingly engaged with the propeller to secure the attachment thereto.

2. An attachment for a propeller comprising 30 curved faces formed to be abuttingly engaged with the faces of the propeller blades and shaped to lessen the effective angle of the propeller blades, and spring-actuated clips secured to the attachment and adapted partially to surround the propeller blades to 35 securely lock the attachment to the propeller.

3. The combination with a propeller having 40 inclined blades and an aperture in each blade, of an attachment having curved, inclined faces, formed to be seated against the correspondingly curved faces of the propeller blades for the purpose of lessening the effective propelling angle of the propeller blades, dowel pins secured to the attachment and adapted to traverse the apertures in the propeller blades, and spring retained clips also secured to the attachment and adapted to 45 partially encircle the propeller blades and to engage the protruding terminals of the dowel pins to lock the attachment to the propeller.

4. The combination with a propeller having inclined blades and an aperture in each blade, of an attachment having curved, inclined faces, formed to be abuttingly seated against the correspondingly curved faces of 55 the propeller blades for the purpose of lessening the effective propelling angle of the propeller blades, dowel pins secured to the attachment and adapted to traverse the apertures in the propeller blades, springs secured 60 to the attachment, and a clip terminally secured to each spring and each having a key slot therein adapted to receive one of the protruding terminals of the dowel pins to lock the attachment to the propeller. 65

5. A boat propeller having relatively fixed blades, and means seated on the working surfaces of said blades on one side and secured thereto, and formed to change the effective angle of said blades whereby their propelling 70 effect in the water will be varied.

6. A boat propeller comprising relatively fixed blades, and a plate fitting the working surfaces of said blades on one side and varying in thickness transversely to lessen the 75 effective angle of the propeller blades to vary their propelling effect.

7. A boat propeller comprising suitable blades and auxiliary blades adapted to fit the working surfaces of said propeller blades on 80 one side, and means for temporarily securing them together, said auxiliary blades being tapered in cross-section whereby, when secured to the propeller blades, their angle to the water will be changed from that of said 85 first mentioned blades and the propelling effect reduced for the purpose specified.

8. A boat propeller comprising a hub and blades radiating therefrom, auxiliary blades adapted to be mounted upon said hub and 90 concentrically with respect to said propeller and fit snugly against the working faces of said propeller blades on one side, said auxiliary blades decreasing in cross-sectional area and presenting a less degree angle than the 95 first mentioned blades to the water to reduce the propelling effect of the propeller blades.

In witness whereof, I have hereunto set my hand this 29th day of April, 1927.

WILLIAM H. WENDT.
